VALVED SIPHON
 George Brase, Los Angeles, Calif.
 (334 Cardinell Court, Mill Valley, Calif.)
 Filed Sept. 13, 1962, Ser. No. 223,418
 3 Claims. (Cl. 4-206)

This invention relates to a liquid level or drain control device or valved siphon for sinks or tanks and the like.

A primary object of my invention is to provide an improved portable valved siphon for sinks and the like that will enable the sink to be filled with water to the desired level and then maintain that level even though additional fresh water is constantly or intermittently added to the sink.

Accordingly, another object of the present invention is to provide a liquid level control device that will remove the water from the sink by drawing it from below the surface to maintain the desired amount of water in the sink. This not only helps in removing debris particles as the dirtier water in the sink is changed, but it also avoids the premature removal of soap suds from the sink.

Another object of my invention is to provide a liquid level control device for sinks that is easily adjustable to control the amount of flow through it so that it can be regulated relative to the input flow rate to give the desired results.

Still another object of my invention is to provide a device which will siphon water from the sink automatically when it reaches a certain predetermined level and which removes the water from the sink at an unusually rapid rate. This feature of my invention enables my device to automatically change a large percentage of water in the sink when a certain level is reached, and will thus automatically drain a portion of the water in the sink or container at periodic intervals or cycles dependent on the rate of flow into the sink.

Another object of the invention is to provide a valved siphon for sinks or tanks that is easily adjustable to operate at two different liquid levels.

Another object of the invention is to provide a portable valved siphon device that will hold itself firmly in position when placed over the conventional outlet.

Yet another object of my invention is to provide a valved siphon device having a visual indicator for setting its valve at any intermediate position from full open to full closed.

A further understanding of the invention, together with more of its objects and advantages will appear from the following detailed description presented in accordance with 35 U.S.C. 112. The use of certain specified materials and the utilization of some details of construction which appear in this description are to be considered as illustrative examples only, rather than limitations upon the invention or upon the claims.

In the drawings:

FIG. 1 is a view in elevation of a valved siphon or drain control device according to the invention illustrating its normal position in use within a sink;

FIG. 2 is an enlarged view in elevation of the valved siphon or drain control device of FIG. 1 with the device connected to maintain the water in the sink at a lower level;

FIG. 3 is another enlarged exploded view in elevation and in section showing the two major components of the valved siphon or drain control device of FIGS. 1 and 2;

FIG. 4 is a plan view in section taken along the line 4-4 of FIG. 3 with views in phantom added to illustrate the various valve positions of the device.

With reference now to the drawings, FIG. 1 shows a liquid level control device or valved siphon 10 embody-

2

ing the principles of the present invention as it appears when in operating position within a sink 11 having a normal outlet drain opening 12 in the bottom thereof. The device 10 is placed directly over the drain opening 12 and is adjustable to control both the liquid level in the sink 11 and the rate of discharge of water from it. The following description of my drain control device will explain how these important functions as well as others are accomplished.

As shown in the exploded detailed view of FIG. 3, my control device 10 comprises basically two slidably connectable tubular conduit members 13 and 14. The lower member 13 is fixedly mounted vertically in or around a circular central opening 15 of a base member 16. The base member 16 is preferably formed of some semi-rigid material such as rubber or a suitable plastic and is slightly concave on its lower side 17 so that it can readily cover and contact the standard drain opening of a sink. As a means of further stabilizing my device when installed I may provide the base member 16 with a magnetic means so that it will firmly engage the sink drain opening. The magnetic means may be in the form of an embedded circular ring 18 or a series of spaced apart single magnets. As another alternative, I may provide magnetic material that is ground up and mixed in with the composition of the base member itself. Such material has previously been used for refrigerator door gaskets and is commercially available.

The upper conduit member 14 of my control device 10 is generally U-shaped and comprises connected parallel legs 19 and 20. Spaced upward from the end of each leg are shoulders 21 and 22 which form enlarged end portions 23 and 24, respectively, each having an inside diameter slightly greater than the outside portion of the lower conduit member 13. Thus, the upper member 14 is adaptable to be slidably attached by either of its end portions 23 or 24 to the lower conduit member 13 depending on the particular depth of water in the sink that is desired. The leg 19 of the upper member 14 has a greater length than the other leg 20 so that either one can be connected to the lower conduit portion 13 to provide for water level control at two different levels.

An important feature of my control device is a controllable valve means 25 which one can regulate the flow of water through the device from maximum flow to the fully closed position. This flow regulation is obtained by imperforate transverse valve members 26, 27 and 28 fixed within and extending partially across the conduit members 13 and 14. These transverse members are adapted to engage and overlap each other when the members 13 and 14 are attached together. By rotating the upper member 14 relative to the lower member 13, the size of the opening past adjacent transverse members can be varied. As shown in FIG. 3, the transverse member 26 in the lower member 13 has a generally semi-circular shape and is located at its upper end. The transverse members 27 and 28 in the upper member 14 of the device 10 also each have a similar generally semi-circular shape and are located in line with the shoulders 21 and 22, respectively, of the end portions 23 and 24. The combined imperforate area of the members 26 and 27 and combined area of the members 26 and 28 exceeds the cross-sectional area of the lower conduit member 13. Thus, when either the end portion 23 or 24 is slidably attached to the lower member 13 the valve member 26 is directly engaged either by a valve member 27 in the long leg 19 of the upper member 14 or the valve member 28 in its short leg 20. When the upper member 14 is rotated relative to the fixed lower member 13 the size of the opening through the valve 25 is varied according to how much the valve members 26, 27 or 28 are overlapped.

As a means of indicating what position the valve member 26 is relative to the valve member 27 or 28 at any given time, and thus how much flow is possible through the device, the upper side of the base member 16 is provided with indicia spaced along its periphery. As shown in FIG. 4, these markings may indicate the various valve positions from fully open at numeral 29 to the fully closed position at numeral 30 and also intermediate settings.

To facilitate the easy manipulation of the device 10 when in use the upper member 14 may be provided with an integral handle portion 31 that extends outwardly so that it can be readily grasped to turn the upper member 14 relative to the lower member 13. The upper and lower members 14 and 13 can be made from any suitable rigid material such as metal or plastic. The latter is preferred because the unique configuration of the various members makes them readily adaptable to well known plastic molding techniques.

In operation, the device 10 is generally placed over the single drain opening 12 before the sink 11 is filled, the magnet 18 within the base portion serving to hold it firmly in place over the drain opening. The upper member 13 is then slidably attached to the lower member 14 with either its longer leg 19 or its shorter leg 20 slidably engaged therewith, depending on the level of water desired in the sink. At the same time the upper member 14 can be rotated relative to the lower member 13 to the particular valve opening desired. With the valve 25 in the fully open position, there is sufficient cross sectional area in the conduit adjacent the engaged valve members 26, 27 and 28 to handle an even abnormally high input flow from the water faucets of the sink. When the sink faucets are turned on and the water fills up in the sink with the valve in the open position, the water will rise through the short pipe leg 20 as shown in FIG. 1, and drain down through the long pipe leg 19 and through the lower member 13 and out the sink drain. This overflowing will continue to hold the sink level at the nominal height of the device 10. Once the liquid level has attained this height the input flow of water can be reduced to a desired rate, the overflow passing out through the device 10. If it is desired to have the water level in the sink go above the device 10 the handle 30 is merely turned to rotate the upper member 14 until the valve member 27 or 28 overlaps more of the valve member 26 of the lower member 13 thus reducing the rate of flow to an amount that is less than that of the flow of water into the sink. If the valve 25 is absolutely closed, the water will continue to rise in the sink, but if only partially closed, the water will rise near the top of the device 10 and create a siphoning effect. When the siphon is established the ambient pressure will cause an increased flow of water through the valve 25 and the rate of discharge of water will thus be increased. This siphoning effect is very beneficial as opposed to a mere overflow type of draining because when it occurs a suction is created at the open end of the upper member 14 which serves to pick up solid particles within the water in the sink that lie well below the surface of the water. Also, since the inlet to the upper member lies considerably below the upper level of the water it is below the soap suds in the sink and thus does not drain them off but rather conserves them for continued use although the water is being circulated beneath it.

When it is desired to drain the sink, this can be done rapidly by adjusting the upper member 14 so that the shorter arm 20 is connected to the lower member 13 and the longer arm 19 extends down near the bottom of the sink as shown in FIG. 2. With the valve moved to the open position, a siphon will now be established, and it will work to drain the sink very rapidly. The suction created during the siphon will tend to draw in

all the solid particles and debris that may have settled to the bottom of the sink.

To those skilled in the art to which this invention relates, many changes in construction and widely differing embodiments and applications of the invention may suggest themselves without departing from the spirit and scope of the invention. The disclosures and the description herein are purely illustrative and are not intended to be in any sense limiting.

I claim:

1. A liquid level control device for use in sinks and the like having an outlet drain opening, said device comprising:

15 a base member having a central opening and an overall area substantially larger than said drain opening and thereby adapted to rest on the bottom of a sink with said central opening in communication with said drain opening;

20 a first tubular conduit section fixed to and supported by said base member and extending upright from said central opening;

25 a second U-shaped conduit section having long and short leg portions, both said leg portions being shorter than said first conduit section and having a diameter slightly larger than said first conduit section, one of said leg portions being telescopically engaged with and rotatable relative to said first conduit section;

30 a first valve means fixed within said first conduit section at its upper end and having an imperforate flat upper surface extending transversely and covering slightly more than one half the cross sectional area of said first conduit section;

35 and a second valve means in the leg portion of said second conduit section engaged with said first conduit section, said second valve means having an imperforate flat lower surface extending transversely and covering slightly more than one half the cross sectional area of the said engaged leg portion, said first and second valve means being engaged together with the valve means in contact to form a variable opening for controlling the flow of liquid through said device when the second conduit section is rotated relative to the first conduit section.

2. A liquid level control device for use in sinks and the like having an outlet drain opening, said device comprising:

45 a flexible base member having an imbedded magnetic stabilizing means for holding the device firmly in position on the bottom of a sink and a central opening for communicating with the drain opening of the sink;

50 a first tubular conduit section fixed to and supported by said base member and extending upright from said central opening;

55 a second U-shaped conduit section having leg portions of unequal length, each said leg portion having an enlarged end portion slightly larger in diameter than said first conduit section, one of said leg portions being telescopically engaged with said first conduit section;

60 a first transverse substantially semi-circular imperforate valve member extending across the top of said first conduit section at its upper end;

65 second and third transverse substantially semi-circular imperforate valve members fixed within the enlarged end portion of each of said leg portion of the second conduit section, the combined area of said first and second transverse valve members and the combined area of said first and third valve members being greater than the cross-sectional area of said first conduit section at its upper end;

70 said first valve member being in flatwise engagement with the valve member of the engaged leg portion when said conduit sections are connected, the rate of flow of liquid through said device being controlled

lable by rotating said conduit sections relative to each other.

3. A liquid level control device for use in sinks and the like having an outlet drain opening, said device comprising:

- 5 a flexible base member with a central opening;
- a first tubular conduit section fixed to and supported by said base member and extending upright from said central opening;
- a second U-shaped conduit section having tubular long 10 and short leg portions, said long leg portion being only slightly shorter than said first conduit section, each said leg portion having an annular shoulder spaced from its end forming an enlarged end portion with a diameter slightly greater than the upper 15 end of said first conduit section, one of said enlarged end portions being telescopically engaged with said first conduit section;
- a first imperforate transverse valve member extending partially across said first conduit section at its upper 20 end;
- second and third imperforate transverse valve members each fixed within a said enlarged leg portion of said second conduit section and extending partially across

said leg portion, the combined area of said first and second transverse valve members and the combined area of said first and third valve members being greater than the cross-sectional area of said first conduit section at its upper end;

said first valve member and the said valve member of the leg engaged with said first conduit section being in constant horizontal flatwise rotational engagement;

whereby the relative annular position of said first and second conduit section determines the amount of overlap of said valve members and the rate of said fluid flow through the device.
